(57) CLAIM

The ornamental design for a step over hitch box, as shown and described.

DESCRIPTION

FIG. 1 is a perspective view of the step over hitch box of the present invention;

FIG. 2 is a right side elevational view, the left side elevational view being a mirror image thereof;

FIG. 3 is a rear elevational view thereof;

FIG. 4 is a front elevational view thereof.

FIG. 5 is a top plan view thereof; and,

FIG. 6 is a bottom plan view thereof.

The broken line showing of environment is for illustrative purposes only and forms no part of the claimed design.
